UNITED STATES PATENT OFFICE.

ANDREW REPPE, OF WINIFRED, MONTANA.

ENGINE.

1,406,896.

Specification of Letters Patent. Patented Feb. 14, 1922.

Application filed October 2, 1920. Serial No. 414,175.

To all whom it may concern:

Be it known that I, ANDREW REPPE, a citizen of the United States, residing at Winifred, in the county of Fergus and State of 5 Montana, have invented new and useful Improvements in Engines, of which the following is a specification.

This invention relates to a novel construction of steam engine, the principal object 10 of the invention being to provide means whereby the steam will act first upon the small end of the piston to move the piston in one direction and will then pass through the low pressure end and act upon the large 15 end of the piston to return the piston to its first position.

Another object of the invention is to provide means whereby the steam will pass through ports in the piston itself thus acting 20 to keep the steam at a high temperature and reducing the amount of steam necessary to run the engine.

Another object of the invention is to provide simple means for causing the controlling 25 valves to permit the steam to act upon the heads of the piston to reverse the engine, thus eliminating the usual reversing gears and eccentrics with their cooperating parts.

Still another object of the invention is to 30 provide an auxiliary inlet for the steam for supplying an extra amount of steam to the high pressure part of the cylinder so as to increase the power of the engine.

This invention also consists in certain 35 other features of construction and in the combination and arrangement of the several parts, to be hereinafter fully described, illustrated in the accompanying drawings and specifically pointed out in the appended 40 claims.

In describing my invention in detail, reference will be had to the accompanying drawings wherein like characters denote like or corresponding parts throughout the several 45 views, and in which:

Figure 1 is a longitudinal sectional view through an engine constructed in accordance with my invention.

Figure 2 is a similar view but taken at 50 right angles of Figure 1.

Figure 3 is a section on line 3—3 of Figure 1.

Figure 4 is a section on line 4—4 of Figure 1, with the large end of the piston over 55 the exhaust ports.

Figure 5 is a section on line 5—5 of Figure 1.

Figure 6 is a face view of the large end of the piston.

Figure 7 is a view of the main steam controlling valve.

In these views 1 indicates the cylinder which is formed of the high pressure part 2 and the enlarged low pressure part 3, the two parts being connected together by a 60 flange 4. This flange carries the outlet port 5 and the interior wall of the part 3 is provided with the grooves 6 which are located adjacent the flange and act to permit the exhaust steam to pass the large end of the 70 piston when the same is at the end of its inner stretch. The part 2 of the cylinder at its outer end is provided with a steam inlet 7 which is connected with the boiler and a cylindrical projection 8 extends inwardly 75 from this end of the part 2 of the cylinder to form a steam chest for the incoming steam. This part 8 is provided with ports 9 adjacent its inner end through which the steam may pass from the chest into the parts 80 2 of the cylinder. The passage of steam through these ports is controlled by the sleeve valve 10 which surrounds the part 8 and which is provided with the ports 11 for registering with the ports 9. The piston 85 A is provided with the small head 12, which engages the part 2 of the cylinder and with a large head 13 located in the part 3 of the cylinder, these heads being connected together by the stem 14 which includes the 90 cylindrical extensions 15 and 16 carried by the heads and the spaced curved portions 17 which are hollow to form the passages 18. The outer ends of these passages extend through the head 13 while their inner ends 95 communicate with the interior of the cylindrical part 15 by means of the ports 19. The cylindrical part 16 is provided with the exhaust ports 20 for permitting the exhaust steam to pass from the low pressure end of 100 the cylinder to the space between the two heads from which it will flow through the exhaust ports 5. A sleeve 21 has screw threaded connection with the cylindrical part 15 and this sleeve is provided with the 105 ports 22 which register with the ports 19 which are connected with the inner ends of the passages. The outer end of the sleeve 21 is closed and a packing gland 23 is placed between its inner end and the inner end of 110

the piston. A piston valve 24 works in the sleeve 21 and a like valve 25 works in the cylindrical part 16, these two valves being connected together by the stem 26. This 5 stem carries the bracket 27 which is located in the space between the two curved parts 17 and has pivoted thereto the rocking lever 28 which has its ends provided with the notched parts 29 for engaging the adjacent 10 ends of the cylindrical parts 15 and 16 to prevent the steam pressure from moving the valves 24 and 25 until the lever is tripped by the trip device 30 which is located at the junction of the two parts of the cylinder 15 with each other. This trip device is carried by a stem 31 which extends alongside of the small part of the cylinder and is slidably attached thereto so that it may be moved to slide the trip device against a trigger 32, 20 fastened to the outer end of the lever 28 for tripping the lever for reversing the engine. Said lever carries a spring 33 for holding it in its tripped position. The piston is connected with the sleeve valve 10 by the rods 25 33', which engage openings formed in ears 34 on the sleeve valve and said rods carry the shock absorbing springs 35. The sleeve valve carries the plunger rods 36 for limiting the movement of said sleeve valve. The 30 cylinder is provided with a pair of piston rods 37 which pass through holes 38 formed in longitudinally extending side extensions 39 formed on the part 2 of the cylinder. These rods pass into the part 3 of the cylinder and are connected with the head 13. As 35 only the exhaust steam enters the space between the cylinder heads, it is not necessary to have packing glands for these rods. The outer ends of the rods are connected together 40 by the cross head 40.

Steam may be supplied directly to the part 2 of the cylinder through the inlet 41 in order to increase the power of the engine or where it is desired to supply steam continuously to the high pressure end of the cylinder.

It will thus be seen that the steam entering the high pressure end of the cylinder will act on the small head of the piston and 50 force the piston outwardly. In this position of the parts the valve 24 will be in a position closing the end of the sleeve while the valve 25 will be in a position with the ports 20 uncovered. Thus the steam at the low pressure 55 end of the piston will flow through the cylindrical part 16 and ports 20 into the space between the heads and through the outlet port 5. As soon as the piston nears the end of the stroke the lever 28 will be tripped by 60 the device 30 so as to permit the steam pressure to move the valves 24 and 25 to uncover the ports 22 and close the ports 20 and these valves will be locked in this position by the opposite end of the lever engaging the cylindrical part 15. The steam will then flow

through the ports 22 and 19 into the passages 18 to the low pressure end of the cylinder and as the ports 20 are closed by the piston valve 25 the steam will act to return the piston to its starting position. As the piston 70 nears the end of its return stroke the trip device 30 will act upon the opposite end of the lever 28 so that the steam pressure will move the valves 24 and 25 into their first positions with the ports 22 closed and the ports 75 20 uncovered. As will be seen the lever 28 is rocked upon its pivotal point, at the end of each stroke, by the trip device 30 engaging the raised end of said lever so as to depress this raised end into engagement with the piston and raise the opposite end out of engagement with the piston, thus locking the valves against movement until the lever is again tripped. When the engine is going over center the head 13 will be directly over 80 the ports or grooves 6 and thus permit the steam at the low pressure end to pass to the exhaust. The movement of the piston will reciprocate the sleeve valve by means of the rods 33 and their springs thus permitting 85 the steam to flow from the chest to part 2 of the cylinder when the piston is at the high pressure end of the cylinder.

When the engine is to be reversed the device 30 is moved inwardly by the stem 31 95 so as to engage the part 32 and thus trip the lever and permit the steam to act in a reverse manner on the piston heads.

Most of the exhaust steam will escape when the engine is going over center through 100 the grooves 6. This will reduce back pressure and give the engine more power. This engine will use very little steam thus reducing the consumption of fuel. The piston is preferably cast in one piece and as the 105 ports are very short and are located within the piston the steam is kept at a high temperature and there is less condensation, thus giving the engine more power. While engines now in use are supplied with steam 110 from the boiler twice to every revolution of the crank shaft, my engine makes a complete revolution with the one supply of steam and this supply of steam is not divided as in most engines but the entire 115 amount acts against one piston head and then the other. If there is any pressure in the exhaust steam located between the piston heads it will act to push the piston in the right direction. By the arrangement of the 120 piston rods the use of packing glands is rendered unnecessary thus reducing expense and giving more power with less friction. As the steam never passes through the same port twice the second port can be larger than 125 the first and the third port larger than the second. This will reduce back pressure and less condensation thus giving more power to the engine.

The auxiliary inlet 41 can be used for 130

starting the engine and it can also be used for giving extra power to the engine. The engine will run with steam going into the high pressure part continuously but one half 5 of this supply of steam would be used only once, while the other half would be used twice. Thus this manner of operation would take more steam and is only intended to be used when the engine is overloaded or for 10 starting. When steam is continuously supplied to part 2 of the cylinder and the piston has moved to the end of its forward stroke and the valves are moved to uncover the ports 22 and close ports 20, some of the steam 15 will pass through the ports and passages into the outer end of part 3 of the cylinder so as to force the piston rearwardly. The steam in chamber 2 continuing to pass through the ports and channels into part 3 20 until the trip device permits the steam in part 3 to change the position of the valves again so that the steam in part 3 can escape to exhaust while the steam in part 2 will be trapped therein and this with the incoming 25 steam will act on the piston to force the same outwardly again. It will thus be seen that some of the steam will simply pass through the ports and passages and flow to the exhaust, while the valves are changing, without 30 acting on the piston.

The engine is reversed by moving the trip device against the trigger. It can also be reversed by turning the engine over center in the opposite direction from which it was 35 running. The engine will revolve in the same direction it did before being stopped unless it is positively reversed.

What I claim is:—

1. An engine of the class described comprising a cylinder provided with a high pressure part and a low pressure part, a piston in said cylinder having a small head operating in the high pressure part and a large head operating in the low pressure part, said 40 large head having exhaust passages therein, the small head having inlet ports therein and the piston body having passages leading from the inlet ports through the large head, a pair of valves controlling the exhaust 45 passages and the inlet ports and actuated by the steam pressure, a stem connecting the valves together, a trip mechanism connected with the stem, means for controlling the supply 50 of steam to the high pressure end of the cylinder and exhaust means carried by the low pressure part of the cylinder.

2. An engine of the class described comprising a cylinder having a high pressure part and a low pressure part, a piston in 60 said cylinder having a small head working in the high pressure part and a large head working in the low pressure part and a stem connecting said ends together, the large head having exhaust passages therein and the 65 small head having inlet ports and the stem

having passages leading from the inlet ports through the large head, piston valves for controlling the inlet ports and the exhaust passages and acted upon by the steam pressure, a stem connecting the valves together, 70 a trip lever carried by the stem for holding the valves against the steam pressure, a slide-able trip device for tripping the lever, means for moving said device to trip the lever at a different point to reverse the engine, the low 75 pressure end of the cylinder carrying exhaust ports and means for supplying steam to the high pressure end of the cylinder.

3. An engine of the class described comprising a cylinder having a high pressure 80 part and a low pressure part, the low pressure part having an exhaust port therein, a piston in the cylinder provided with a small head working in the high pressure part and a large head working in the low pressure 85 part, said heads having inwardly extending cylindrical parts provided with ports and a stem connecting said heads together, said stem having a passage therein connecting the ports in the cylindrical part of the small 90 head with the outer face of the large head, piston valves working in said cylindrical parts and acted upon by the steam pressure to cover and uncover the ports in said cylindrical parts, a stem connecting said valves 95 together, a trip lever carried by said stem for holding the valves against pressure, a movable trip device for tripping the lever and means for supplying steam to the high 100 pressure part of the cylinder.

4. An engine of the class described comprising a cylinder having a high pressure part and a low pressure part, the low pressure part having an exhaust port, a piston in said cylinder having a small head working in the high pressure part and a large head working in the low pressure part, said piston having passages for connecting the high pressure part with the low pressure part and the low pressure part with the exhaust, valves for controlling said passages and acted upon by the steam pressure, a stem connecting said valves together, a trip mechanism for holding the valves against the pressure and means for supplying steam to 105 the high pressure part, said means including a sleeve valve and means for actuating the same by the piston.

5. An engine of the class described comprising a cylinder having a high pressure 120 part and a low pressure part, the low pressure part having an exhaust port therein and grooves in its walls adjacent said port, a piston provided with a small head working in the high pressure part and a large head 125 working in the low pressure part, said large head passing over the grooves when the engine is on center, said piston having passages connecting the high pressure part with the low pressure part and other passages 130

4
connecting the low pressure part with the exhaust, piston valves for controlling said passages and acted upon by the steam pressure, a stem connecting said valves together, 5 trip mechanism for holding the valves against the pressure and means for supplying steam to the high pressure part.

6. An engine of the class described comprising a cylinder having a high pressure 10 part and a low pressure part having an outlet port, a piston in said cylinder provided with a small head working in the high pressure part and a large head working in the low pressure part, said piston having passages for connecting the high pressure part with the low pressure part and other 15 passages connecting the low pressure part with the exhaust, piston valves for connecting said passages and acted upon by the steam pressure, a stem connecting said valves together, a trip mechanism connected with the stem for holding the valves against the steam pressure, means for introducing steam into the high pressure part and a pair of piston 20 rods passing into the exhaust side of the low

pressure part and connected with the large head of the piston.

7. An engine of the class described comprising a cylinder having a high pressure part and a low pressure part, the low pressure part having an exhaust port, a piston in said cylinder provided with a small head working in the high pressure part and a large head working in the low pressure part, 30 passages in said piston connecting the high pressure part with the low pressure part and other passages connecting the low pressure part with the exhaust, valves for controlling said passages and acted upon by the steam pressure, a stem connecting said valves together, a trip mechanism connected with the stem for holding the valves against the steam pressure, valve controlled means for introducing steam into the high pressure part, 35 means for actuating such means by the movement of the piston and an auxiliary steam supply connected with the high pressure part. 40

In testimony whereof I affix my signature.
ANDREW REPPE.
